Carl F. Schaus, Hagaman, N. Y., assignor to General
Electric Company, a corporation of New York

Application November 26, 1956, Serial No. 43,936

Term of patent 14 years

(Cl. D26—13)

Fig. 1

Fig. 2

Fig. 3

Figure 1 is a front perspective view of an electric circuit breaker, showing my new design;

Figure 2 is a rear elevational view; and

Figure 3 is a side elevational view, the opposite side being substantially a mirror image thereof.

The broken line showing of legible matter in the drawing is for illustrative purposes only.

I claim:

The ornamental design for an electric circuit breaker, as shown and described.
